DESIGN FOR A PORCELAIN LIGHTING FIXTURE

R. Guy Cowan, Syracuse, N. Y., assignor to Pass
& Seymour, Inc., Syracuse, N. Y., a corporation
of New York

Application July 15, 1935, Serial No. 57,657

Term of patent 7 years

To all whom it may concern:

Be it known that I, R. Guy Cowan, a citizen of the United States and resident of Syracuse, county of Onondaga, and State of New York, have invented a new, original, and ornamental Design for Porcelain Lighting Fixture, of which the following is a specification, reference being had to the accompanying drawing, forming a part thereof, and in which:

Figure 1 is a side elevation of a porcelain lighting fixture embodying the present design;

Figure 2 is a plan view thereof; and

Figure 3 is a partial section on line 3—3 of Figure 1.

I claim:

The ornamental design for a porcelain lighting fixture, substantially as shown.

R. GUY COWAN.
